WIDENER FOR USE IN SAW KERFS OF TIMBER

Filed June 27, 1949

UNITED STATES PATENT OFFICE

2,541,894

WIDENER FOR USE IN SAW KERFS OF
TIMBERClyde G. Swant and John A. Morigeau,
Arlee, Mont.

Application June 27, 1949, Serial No. 101,576

11 Claims. (Cl. 254—133)

1

This invention relates to improvements in accessories employed by lumbermen in felling trees and cutting up logs.

In felling trees it is common practice to use a saw, either manually or mechanically operated and, as the sawing through of the trunk progresses, the weight of the tree above the saw and above the kerf or cut made by the latter generally causes the saw to bind in the cut. Expedients employed to hold the cut open so that sawing may be continued are wooden and metal wedges, for example, but these have been found undesirable and unsatisfactory. For instance, in employing wedges, it is necessary that the cut extend into the trunk a distance sufficient for the wedge to enter the cut far enough to spread the cut and yet not interfere with the saw. In other cases, where metal wedges are employed in conjunction with mechanically-operated saws, the former are sometimes driven into the cut so far and with force enough to break or damage the saw and cause metallic splinters to be projected from the cut. In still other cases, the driven wedge will be accidentally forced out of or spring from the cut by the weight of the tree upon it.

An important object of this invention is the provision of a lumberman's accessory in felling trees, splitting logs and similar operations, which accessory may be employed after the cut is but a few inches deep beyond the back of the saw or saw frame.

Another important object is to provide an accessory of this kind which will not interfere in any way with the operations of the saw, will not damage the saw or saw frame and will not be apt to be forced accidentally from a cut.

Still another important object of the invention is to provide a sturdy and powerful device for holding open a cut in a tree or log.

Another object is to provide a device which is primarily employed as stated but may also be employed in expediting and directing the fall of a cut into tree or the like.

Other objects and advantages of the invention will be apparent during the course of the following detailed description of the invention, taken in connection with the accompanying drawing, and in which drawing

Fig. 1 is a view mostly a side elevation of the new device, showing the position of parts when the device is being operated.

Fig. 2 is a view largely in end elevation, being the end to the right in Fig. 1.

Fig. 3 is a view along the lines of Fig. 1 but illustrating a subsequent step in the operation of the new device.

Fig. 4 is a transverse vertical section, substantially on the line 4—4 of Fig. 3 showing the device inserted into a kerf.

2

Fig. 5 is a horizontal section, substantially on the line 5—5 of Fig. 3.

In the drawing, wherein for the purpose of illustration is shown a preferred embodiment of the invention and wherein similar reference characters designate corresponding parts throughout the several views, the new device, which may be termed a cut or kerf widener for cuts or kerfs in tree trunks and the like, is shown to comprise a base portion A, standard B, movable (reciprocating) tongue-carrying portion C, tongue D, means E for moving or reciprocating the portion C carrying the tongue D, with reference to the base portion A, means F for limiting the extent of movement of the portion C and tongue D, a fixed handle or hand hold G, and a removable handle H.

The base portion A is, preferably a flat plate, having a substantially straight edge 10, which faces the base of the cut or cleft when the device is inserted into the cut or cleft, a substantially flat upper face 11 and a like lower face 12, with a centrally disposed opening as a recess 13 extending from the edge 10 toward the opposite or outer edge 14 and from face 11 to face 12. Preferably the closed end or base of the recess may be arcuate, with the wall of the closed end convex, whereby a semi-cylindrical section 15 of the base portion is provided. There is, preferably, a pair of pivot pin-accommodating sections, as a pair of ears 16, forming a part of the base portion A and projecting upwardly therefrom from lines extending radially from the axis of the semi-cylindrical portion 15 and with the ears 16 substantially 180° apart. The ears 16 carry pivot pin-accommodating perforations with their axes substantially normal to the plane of the edges 10. The sections of the base portion A beyond these ears 16 to the edge 10 may be termed the cut-inserted sections of the new device.

Secured to the base portion A is a suitable elongated standard or upright B which is, preferably, a tube having a stop-accommodating, screw-threaded perforation 20 intermediate its ends. The standard B may be welded to the base portion A at the section 15 so the former will extend substantially vertically therefrom at the base of the recess 13. Preferably, the outer face 21 of the standard B is smooth.

Slidable vertically along the standard B is a suitable movable tongue-carrying portion C, which may be an elongated tube, having a longitudinally-extending stop-accommodating slot 25 intermediate its ends, and two pairs of pivot pin-accommodating sections, as pairs of ears 26, extending outwardly from, preferably, its upper end part. Each ear of each pair of ears 26 is spaced apart from its associated ear, whereby an opening 27 is provided and each ear has a pivot pin-accommodating perforation, with the perfo-

rations of each pair axially aligned. The openings 27 are disposed substantially 180° apart.

Carried at the lower end of the portion C, and normally disposed within the recess 13, is a tongue D, which is preferably the same thickness as that of the base portion A and extends to the edge 10 of the base portion A and has a substantially straight edge 30, the plane of which preferably coincides with the plane of the edge 10. This tongue D may be welded to the portion C, as along the lower edge of the latter. The tongue D may be termed another cut-inserted section of the new device. It has an upper face 28 and lower face 29 similar to the faces 11 and 12.

Means E for moving (as elevating and lowering) the portion C carrying the tongue D may include a pair of socketed rocker arms 35 pivotally carried, as by pivot pins 36, at their lower end portions by the ears 16, since the rocker arms are bifurcated at their lower end portions so as to slidably and rockably fit over the ears 16. Each arm has an open opposite end providing a mouth for its socket, and carries an exteriorly screw threaded projection or shank portion 37 terminating in a bifurcated head 38 provided with a pair of axially-aligned pivot pin-accommodating perforations, operatively disposed with the axes of the perforations in parallelism and in parallelism with the perforations of the ears 16. The screw-threaded shank portions 37 are slidable within the sockets of the rocker arms and extend outwardly thereof. Pivotally carried by each head 38 is an L-shaped lever 39 with the pivotal connection intermediate the upper arm 40 and lower arm 41 of the lever. The pivotal connections may be conventional, cotter pin-retained pivot pins 42. Each arm 40 is provided with a pivot pin-accommodating perforation adjacent its free end, through which extends a suitable pivot pin 43 to pivotally connect the levers 39 to the ears 26 of the portion C. Extending from intermediate the ends of the lower arm 41 to the upper end of the arm 40 is a dual-function stop portion 44. This may be a rod, bent or otherwise fashioned to form an obtuse angle, and with its upper end face 45 constructed and arranged to engage the outer face of the portion C when the lever 39 carrying the stop portion 44 is rocked to a position with the lever arm 41 at its highest rocked position (as the right-hand lever 39 in Figure 1). The juncture of the stop portion 44 and arm 41 constitutes a stop for a suitable handle G to be described. Suitable adjustable stop means 46 are provided for each screw threaded shank portion 37 and each preferably comprises a nut with its threads engaging those of the shank portion and its lower face adapted to abut the upper end edge of its associated rocker arm. To limit movement of the rocker arms 35 toward the portion C, the lever arms 40 contact the bights 47 of the bifurcated heads 38 as is clear in Figure 1.

Means F for limiting the extent of raising and lowering of the portion C and tongue D may be a suitable screw threaded cylindrical stop screwed into the perforation 20 and extending into the slot 25 to slide therewith upon movements of the portion C and limit the extent of such movements when it contacts either end wall of the slot 25.

A suitable fixed handle or hand hold G may be provided, as a U-shaped rod, welded or otherwise secured to the exterior of the portion C and overlaying the edge 14 of the base portion A.

A suitable handle H may be provided, having

a socketed lower end portion 50 adapted to fit over the free end of either lever arm portion 41, but will be stopped, so it cannot strike the ears 26 when it is mounted upon the lever arm portion.

The openings 21 permit the dual-function stop portion to ride therein, as shown in dotted lines in Figure 1 and, of course, accommodate the upper end sections of the upper lever arm portions 40. They also prevent dead centering of the rocker arms 35 when the face 45 contacts the portion C, as is apparent in Figures 1 and 3, and they additionally brace the lever arms.

With the faces 11 and 28 in the same plane (or the face 28 even above the plane of the face 11 of the cut will permit insertion), the cut-inserted sections of the base portion A and tongue D are inserted into the kerf or cut 55 of a tree trunk or a log, such as in Figure 4, by the lumberman grasping the handle or hand hold G. If the kerf permits an insertion with the tongue D raised, the lumberman should initially manipulate the new device before insertion into the cut, by swinging one lever 39 to a position similar to that of the right hand lever of Figure 1 (but with the adjustable stop means 46 associated therewith spaced above the upper end of the associated rocker arm 35). He then turns the stop means 46 until it engages this upper end (as shown in Figure 1) and then swings this lever to the position of the right-hand lever 39 of Figure 3. If this step is accomplished while the cut-inserted sections are within the kerf 55, he employs the handle H, giving himself added leverage.

With the right-hand lever as in Figure 3, he moves the left-hand lever 39 to its position as in Figure 3 threads the stop means 46 associated therewith downwardly and then swings this lever (with use of the handle H) into the position of the right-hand lever of Figure 3. Each movement to a position like that of the left-hand lever of Figure 1 or right-hand lever of Figure 3 elevates the tongue D and, consequently, widens the kerf 55 when the device is in use. When the cut has been completed, so that the tree falls or the pressure of the device in the cut causes it to fall, the device may be removed and the tongue D lowered to a position so the device may be re-employed by manipulation of the stop means 46 and levers 39 as is now apparent.

We prefer to construct the new device of suitable high-tensile steel, such as chromium alloy steel, but may employ other suitable metals or alloys.

The new device is readily portable, may be carried about by the lumbermen and used on standing timber, logs, or wherever a kerf or split has been made for insertion of the cut-inserted sections.

Since the device is not a wedge but an expandable device in which expansion of the parts is accomplished, not by jaws, but by a part (the tongue D) moving away from the base portion A in a substantially straight line, there is no tendency for the device to spring from the kerf (as a wedge is apt to do).

From Figure 4 it is now clear that the cut-inserted sections of the new device need be inserted only a short distance into a cut 55. In fact the insertion may be governed by the position of the back of the saw or like conditions, or the sections mentioned may be inserted until the portion C contacts the tree trunk (although this is not advised).

It is now obvious that the new device may be employed in a vertical position, a horizontal po-

sition or an inclined position and will operate efficiently in any of these positions, that there is no need of a maul or the like (as required with a wedge) nor are any blows upon the device necessary in order to operate it.

Various changes may be made to the form of the invention herein shown and described without departing from the spirit of the invention or scope of the claims.

What is claimed is:

1. In a tree trunk kerf widener, a cut-inserted section having a face in contact with one face of the cut, a movable cut-inserted section having a face in contact with the opposite face of the cut, means slidably connecting said sections, and means to move said movable section toward and away from the other section with the planes of said faces of said sections substantially normal at all times to the path of travel of said movable section.

2. In a widener for a kerf in a tree trunk, a base portion having a cut-inserted section provided with a cut surface-containing face and with an opening; a movable portion having a tongue providing a cut-inserted section, said tongue having a cut surface-contacting face and said tongue being normally disposed in said opening, and means movably connected with said portions to selectively move said tongue into and out of said opening in a path substantially normal to said faces.

3. In a widener for a kerf in a tree trunk, a base portion having a pair of spaced-apart pivot pin-accommodating sections and a cut-inserted section said last section being provided with an opening; a movable portion having a tongue providing a second cut-inserted section, with said tongue being normally accommodated in said opening, said movable portion also provided with a pair of pivot pin-accommodating sections spaced an equal distance from the first-named pivot pin-accommodating sections; means to selectively move said tongue into and out of said opening, including a pair of rocker arms pivotally carried by said first pivot pin-accommodating sections at like ends of each arm, a projection carried by, projecting from and slidably longitudinally of each arm, each of said projections having a head, a pair of levers, one pivoted to one head and the other pivoted to the other head intermediate the ends of the levers, with one end of one lever pivoted to one of said second pivot pin-accommodating sections and a like end of the other lever pivoted to the other of said second pivot pin-accommodating sections; and means manually movable along said projections to adjusted fixed positions to limit sliding movements of said projections with reference to said rocker arms.

4. In a widener for a kerf in a tree trunk, a base portion having a pair of spaced-apart pivot pin-accommodating sections and disposed substantially 180° apart, and a cut-inserted section said last section being provided with an opening; a movable portion having a tongue providing a second cut-inserted section, with said tongue being normally accommodated in said opening, said movable portion also provided with a pair of pivot pin-accommodating sections spaced an equal distance from the first-named pivot pin-accommodating sections and disposed substantially 180° apart; means to selectively move said tongue into and out of said opening, including a pair of rocker arms pivotally carried by said first pivot pin-accommodating sections at like ends of each arm, a projection carried by, projecting from and slidably longitudinally of each arm,

from and slidably longitudinally of each arm, each of said projections having a head, a pair of levers, one pivoted to one head and the other pivoted to the other head intermediate the ends of the levers, with one end of one lever pivoted to one of said second pivot pin-accommodating sections and a like end of the other lever pivoted to the other of said second pivot pin-accommodating sections; and means manually movable along said projections to adjusted fixed positions to limit sliding movements of said projections with reference to said rocker arms.

5. In a widener for a kerf in a tree trunk, a base portion having a pair of spaced-apart pivot pin-accommodating sections and disposed substantially 180° apart, and a cut-inserted section said last section being provided with an opening; a movable portion having a tongue providing a second cut-inserted section, with said tongue being normally accommodated in said opening, said movable portion also provided with a pair of pivot pin-accommodating sections spaced an equal distance from the first-named pivot pin-accommodating sections and disposed substantially 180° apart; means to selectively move said tongue into and out of said opening; including a pair of rocker arms pivotally carried by said first pivot pin-accommodating sections at like ends of each arm, a projection carried by, projecting from and slidably longitudinally of each arm, each of said projections having a head, a pair of levers, one pivoted to one head and the other pivoted to the other head intermediate the ends of the levers, with one end of one lever pivoted to one of said second pivot pin-accommodating sections and a like end of the other lever pivoted to the other of said second pivot pin-accommodating sections; means manually movable along said projections to adjusted fixed positions to limit sliding movements of said projections with reference to said rocker arms; and means to limit movement of said tongue out of said opening.

6. In a widener for a kerf in a tree trunk, a base portion having a pair of spaced-apart pivot pin-accommodating sections and a cut-inserted section said last section being provided with a recess; a movable portion having a tongue providing a second cut-inserted section, with said tongue being normally accommodated in said recess, said movable portion also provided with a pair of pivot pin-accommodating sections spaced an equal distance from the first-named pivot pin-accommodating sections; means to selectively move said tongue into and out of said recess, including a pair of rocker arms pivotally carried by said first pivot pin-accommodating sections at like ends of each arm, a projection carried by, projecting from and slidably longitudinally of each arm, each of said projections having a head, a pair of levers, one pivoted to one head and the other pivoted to the other head intermediate the ends of the levers, with one end of one lever pivoted to one of said second pivot pin-accommodating sections and a like end of the other lever pivoted to the other of said second pivot pin-accommodating sections; and means manually movable along said projections to adjusted fixed positions to limit sliding movements of said projections with reference to said rocker arms.

7. In a tree trunk kerf widener, a base portion having a cut-inserted section and a section joining said first section with a recess extending into said first section and terminating at said second section; a standard carried by said base portion

and joining said base portion at said second section and at the base of said recess; a movable portion, slideable longitudinally along said standard, having an end adjacent the juncture of the standard and base portion; a tongue carried at the end of said movable portion adjacent said juncture and normally disposed within said recess, said tongue providing a second cut-inserted section; and means providing a step-by-step movement of said movable portion along said standard.

8. In a tree trunk kerf widener, a base portion having a cut-inserted section and a section joining said first section with a recess extending into said first section and terminating at said second section; a standard carried by said base portion and joining said base portion at said second section and at the base of said recess; an elongated movable portion, telescopically carried by said standard, having an end adjacent the juncture of the standard and base portion; a tongue carried by and projecting normal to said movable portion at the end of said movable portion adjacent said first end, said recess accommodating said tongue and said tongue providing a second cut-inserted section; and means providing a step-by-step movement of said movable portion along said standard.

9. In a widener for a kerf in a tree trunk, a base portion having a pair of spaced-apart pivot pin-accommodating sections and a cut-inserted section said last section being provided with an opening; a movable portion having a tongue providing a second cut-inserted section, with said tongue being normally accommodated in said opening, said movable portion also provided with a pair of pivot pin-accommodating sections spaced an equal distance from the first-named pivot pin-accommodating sections; means to selectively move said tongue into and out of said opening, including a pair of rocker arms pivotally carried by said first pivot pin-accommodating sections at like ends of each arm, a projection carried by, projecting from and slideable longitudinally of each arm, each of said projections having a head, a pair of levers, one pivoted to one head and the other pivoted to the other head intermediate the ends of the levers, with one end of one lever pivoted to one of said second pivot pin-accommodating sections and a like end of the other lever pivoted to the other of said second pivot pin-accommodating sections; means manually movable along said projections to adjusted fixed positions to limit sliding movements of said projections with reference to said rocker arms; and means to limit movement of said rocker arms and the other ends of said levers outwardly, comprising a stop portion carried by each lever and having end faces with said movable portion being disposed within the paths of travel of said end faces when said rocker arms are rocked outwardly to predetermined positions.

10. In a widener for a kerf in a tree trunk, a base portion having a pair of spaced-apart pivot pin-accommodating sections and a cut-inserted section said last section being provided with an opening; a movable portion having a tongue providing a second cut-inserted section, with said tongue being normally accommodated in said opening, said movable portion also provided with a pair of pivot pin-accommodating sections spaced an equal distance from the first-named pivot pin-accommodating sections; means to

selectively move said tongue into and out of said opening, including a pair of rocker arms pivotally carried by said first pivot pin-accommodating sections at like ends of each arm, a projection carried by, projecting from and slideable longitudinally of each arm, each of said projections having a head, a pair of levers, one pivoted to one head and the other pivoted to the other head intermediate the ends of the levers, with one end of one lever pivoted to one of said second pivot pin-accommodating sections and a like end of the other lever pivoted to the other of said second pivot pin-accommodating sections; means manually movable along said projections to adjusted fixed positions to limit sliding movements of said projections with reference to said rocker arms; and means to limit movement of said rocker arms and the other ends of said levers outwardly, comprising a stop portion carried by each lever and having end faces with said movable portion being disposed within the paths of travel of said end faces when said rocker arms are rocked outwardly to predetermined positions.

11. In a widener for a kerf in a tree trunk, a base portion having a pair of spaced-apart pivot pin-accommodating sections and a cut-inserted section said last section being provided with an opening; a movable portion having a tongue providing a second cut-inserted section, with said tongue being normally accommodated in said opening, said movable portion also provided with a pair of pivot pin-accommodating sections spaced an equal distance from the first-named pivot pin-accommodating sections, means to selectively move said tongue into and out of said opening, including a pair of rocker arms pivotally carried by said first pivot pin-accommodating sections at like ends of each arm, a projection carried by, projecting from and slideable longitudinally of each arm, each of said projections having a head, a pair of two-armed, L-shaped levers, one pivoted to one head and the other pivoted to the other head intermediate the ends of the levers, with one end of one lever pivoted to one of said second pivot pin-accommodating sections and a like end of the other lever pivoted to the other of said second pivot pin-accommodating sections; means manually movable along said projections to adjusted fixed positions to limit sliding movements of said projections with reference to said rocker arms; and means to limit movement of said rocker arms and the other ends of said levers outwardly and to brace said levers, comprising an elongated portion carried by each lever and having one end face with said movable portion being disposed within the path of travel of said end face when either of said rocker arms is rocked outwardly to a predetermined position, said elongated portion having a second end face secured to one of the arms of said lever and secured to the other arm of said lever.
